UNITED STATES PATENT OFFICE.

ARTHUR G. SAILER, MASSILLON, OHIO, ASSIGNOR OF ONE-HALF TO LAWRENCE P. MELVIN, OF MASSILLON, OHIO.

GAS-HEATED SAD-IRON.

1,097,881.

Specification of Letters Patent.

Patented May 26, 1914.

Application filed April 22, 1912. Serial No. 692,219.

To all whom it may concern:

Be it known that I, ARTHUR G. SAILER, a citizen of the United States, residing at Massillon, in the county of Stark and State 5 of Ohio, have invented a new and useful Gas-Heated Sad-Iron, of which the following is a specification.

In gas-heated sad-irons it is a well known fact that there is little difficulty in obtaining 10 the necessary heat in the iron itself. Some of the difficulty however is the regulation or control of the heat in the iron, provision for proper distribution, the consumption of the minimum amount of gas.

15 The present invention relates to improvements in the construction of sad-irons of the class mentioned, the objects of the present improvement being to more perfectly distribute and control the heat in the iron, to 20 improve combustion and at the same time provide a pilot light.

These objects together with other objects readily apparent to those skilled in the art 25 are attained by the construction and arrangement illustrated in the accompanying drawings, in which—

Figure 1 is a longitudinal vertical section on the median line illustrating an iron embodying my improvements. Fig. 2 is a transverse section on line 2—2, Fig. 1. Fig. 3 is a detached perspective view of the burner. Fig. 4 is a rear end view of the sad-iron showing portions of the main and pilot gas pipes. Fig. 5 is a view showing a portion 35 of the sad-iron illustrating the valve connection for the pilot gas pipe and illustrating the position of the valves with reference to each other. Fig. 6 is a horizontal section showing the main supply passage 40 open and the pilot passage closed. Fig. 7 is a similar view showing the main supply pipe partially closed and the pilot passage partially open.

Similar numerals of reference indicate 45 corresponding parts in all the figures of the drawings.

In the accompanying drawings, 1 represents the hollow body of the iron which is open at its top, the cover-plate 2 being 50 adapted to properly close the top of the hollow body. To the cover-plate 2 is attached in the usual manner the handle 3. In the drawings I have illustrated the handle attached by suitable lug bolts 4 but it is immaterial as to the method of attaching the

handle. Within the hollow body 1 is located the burner 5, which burner consists of tapered pipe, the chamber of which is illustrated in cross section in Fig. 2. For the purpose of providing a chamber of sufficient 60 size at the gas intake end of the hollow body 1 the intake end of the burner is provided with the upwardly extending portion 6. Said upwardly extending portion also serves to guide or move the gas for the pilot light 65 downward or toward the bottom of the hollow body 1.

For the purpose of supporting the burner its sides are provided with the integral blades or flanges 7, which blades or flanges 70 are preferably located in the same horizontal plane. Below the blades or flanges 7 are located a series of vertical plates or partitions 8, which plates or partitions are for the purpose, first, of supporting and holding 75 the burner and removing the strain from its attached end, and second, the vertical plates or partitions 8 produce separate chambers or pockets whereby the flame emanating from the burner is better confined and a 80 more even heat throughout the entire length of the sad iron maintained. By tapering the burner from its intake end toward the rear end, the size of the chamber is gradually reduced by which arrangement the gas is more 85 evenly distributed, thereby producing a more uniform flame throughout the entire length of the burner and consequently, a more uniform heat through the entire length of the sad iron proper. The bottom or underside 90 of the burner is provided with a series of transverse slits 9, which transverse slits are located on the underside of the burner and directly over the various chambers between the vertical partitions 8.

For the purpose of allowing the flame to be continuous from end to end at that portion of the burner provided with the slits 9, the tops of the partitions 8 are cut out or recessed so as to provide a continuous 100 chamber directly below the plates or flanges 7, but at the same time partially separating the lower portion of the flame and confining the same in the different chambers.

For the purpose of aiding combustion the side walls of the hollow body 1 are provided with the air intake apertures 10. For the purpose of providing means for connecting the burner 5 to the hollow body 1, the flanges 11 are provided and are connected to the 110

body in the usual manner by bolts or their equivalents. For the purpose of providing a pilot light the pilot supply pipe 12 is provided which is connected to the head 13. The burner 5 is provided with the passage 14, which registers with the passage 16 formed in the head 13. To the head 13 is attached the main supply pipe 17 in any convenient and well known manner, which supply pipe leads to any source of supply.

The passage 16 formed in the head 13 is curved so as to bring the intake opening in a true vertical position, by which arrangement the supply of fuel is free to pass into the burner without first being shunted toward the bottom of the burner. By this arrangement the fuel is better distributed and a more even flame is produced, owing to the taper of the top of the burner, which tapered top forces the fuel toward the bottom of the burner as it moves along toward the inner end of said burner. The lower inclined portion at the intake end of the burner has a tendency to prevent the gas from being forced through the adjacent slits 9 to a greater extent than the remaining or more remote slits, thereby producing an even and uniform flame, throughout the entire length of the burner.

When it is desired to heat the sad-iron proper the valves 18 and 19 are both opened and gas supplied to the burner 5. But at this time the supply of gas is cut off from the pilot pipe 12. The valve 18 is an ordinary needle valve and is for the purpose of regulating the amount of gas to be supplied to the main burner. When it is desired to extinguish the main burner the valve 19 is moved so as to close the main passage 19^a and open the pilot supply passage 20^a and supply fuel to the pilot tube 12, the action being such that the supply of fuel to the pilot pipe 12 will be such that the pilot light will be ignited before the main light has been extinguished, thereby lighting the pilot light and extinguishing the burner. By the reverse action of the valve 19 the fuel supply is cut off to the pilot light, but supplied to the main burner, the main burner being started or ignited from the pilot light.

It will be understood that by tapering the top portion of the burner and locating said tapered portion above the slits 9 the fuel will strike the bottom of the burner at an angle throughout the entire length of the burner thereby supplying an equal amount of fuel to each and all of the slits by means of which a uniform flame and uniform heat is maintained.

For the purpose of better feeding fuel to all of the slits the bottom of the burner is formed straight, said straight bottom being located directly below the tapered top portion of the burner. It will also be understood that by providing the vertical parti-

tions 8 and spacing said partitions the flame emanating from the burner 5 will be confined in the chambers between the partitions and the burner support flanges, thereby spreading the flame toward the sides of the hollow body, by which arrangement a uniform heat is produced upon the entire surface of the bottom.

For the purpose of supplying a mixture of air with the gas which supplies the pilot light the air intake 12^a is provided and is so located that the air will be taken into the passage leading to the lower portion or chamber of the hollow body 1. For the purpose of supplying fuel for the pilot light the passage 13^a is provided which passage communicates with the passage 14^a formed in the head 13.

Having fully described my invention what I claim as new and desire to secure by Letters Patent, is—

1. In a gas-heated sad-iron the combination of a hollow body, a cover plate connected thereto, a hollow burner provided with an elongated chamber transverse to the length of the burner and the burner tapered from its intake end, a series of slits located in the lower portion of the burner, flanges located upon opposite sides of the burner, a series of vertical partition plates located in the lower portion of the hollow body, said partition plates located in the lower portion of the hollow body and below the burner, said partition plates provided with recesses upon their upper edges and the burner flanges adapted to rest upon the upper edges of the partition plates, and means for supplying fuel to the burner, substantially as and for the purpose specified.

2. In a gas heated sad-iron, the combination of a hollow body and a cover therefor, a burner provided with an upwardly extended portion at its intake end, said burner tapered from its intake end and provided with a series of slits, a series of partition plates located below the burner, flanges extended from the sides of the burner, said flanges adapted to support the burner, and means for supplying fuel to the burner, substantially as and for the purpose specified.

3. In a gas heated sad-iron, the combination of a hollow body and a cover therefor, a burner provided with an upwardly extended portion at its intake end, said burner tapered from its intake end and provided with a series of slits, a series of partition plates located below the burner, flanges extended from the sides of the burner, and said flanges adapted to support the burner, a main supply pipe communicating with the intake end of the burner and a pilot supply pipe communicating with the hollow body below the intake end of the burner, substantially as specified.

4. In a gas heated sad iron, the combina-

tion of a hollow body and a cover therefor, a burner provided with flanges located upon opposite sides of the burner, a series of gas passages extended through the lower portion of the burner and between the flanges, a series of vertical plates located within the hollow body and spaced from each other, said vertical plates located below the oppositely disposed flanges upon the burner and means for supplying fuel to the burner.

5 5. In a gas heated sad iron, the combination of a hollow body and a cover therefor, a series of partitions located in the lower portion of the hollow body, a burner provided with laterally extending flanges and a series of slits extended through the burner and between the laterally extending flanges, said flanges adapted to rest upon the top edges of the partitions.

6. In a gas heated sad iron, the combination of a hollow body and a cover therefor, a series of partitions located in the lower portion of the hollow body, a burner provided with laterally extending flanges and a series of slits extended through the burner and between the laterally extending flanges, said flanges adapted to rest upon the top edges of the partitions, said partitions provided with cut out portions adapted to receive the lower portion of the burner.

10 15 20 25 30 In testimony that I claim the above, I have hereunto subscribed my name in the presence of two witnesses.

ARTHUR G. SAILER.
